UNITED STATES PATENT OFFICE.

JOHN WALTER GRANTLAND, OF CINCINNATI, OHIO.

LUBRICATING DEVICE.

Application filed March 4, 1922. Serial No. 541,188.

To all whom it may concern:

Be it known that I, JOHN WALTER GRANTLAND, a citizen of the United States, and residing at Cincinnati, in the county of Hamilton and State of Ohio, have invented a new and useful Improvement in Lubricating Devices, of which the following specification is a full disclosure.

This invention relates to a device for forcibly delivering lubricant into locomotive engine cylinders, in measured quantity, approximately proportionate to the distance of locomotive travel.

An object of the invention is the provision of means for positively, regularly and forcibly introducing definite quantities of lubricant into an engine cylinder, against steam pressure.

The invention is mainly directed to the structure and operation of a combined valve and piston, attached within an oil reservoir and positively operable for pumping oil into the steam pipe adjacent the cylinder, through means connected with and movable by a locomotive driving gear.

Other objects and certain advantages will be disclosed in the description of the drawings, in which:

Figure 1 is a central section through the lubricating device, which is operated to deliver lubricant directly into the steam pipe.

Fig. 2 is a sectional elevation at right angles to Fig. 1.

Fig. 3 is a fragmentary side elevation of a locomotive showing my lubricating system installed thereon.

Figs. 4 and 5 are detail views showing the operation of the valve actuating ratchet mechanism.

The invention herein is principally directed to an apparatus for forcibly delivering a measured quantity of lubricant to the engine cylinder of a locomotive in timed periods or frequency, while the engine is in operation, the structural details of the mechanism employed forming the principal feature thereof.

The present invention employs a mechanically operated lubricant delivery device attached preferably to the running board of the locomotive, with its reservoir in communication with the steam pipe, between the boiler and steam chest, the device being ac-

cessible for filling and adjustment by the attendants while the locomotive is running.

The lubricant conveyor is connected to the steam pipe, in such a manner, that a measured quantity of lubricant is delivered and distributed therewithin, mixed with steam and carried to the cylinder, at definite periods, conformably to engine requirements, calculated upon a mileage basis. This method of delivery, supplies the cylinder with the proper amount of lubricant while in operation, and also provides means for an approximate computation of the amount of oil required for a given run. This, in railroad service, is an important factor, inasmuch as the oil requisition is on a mileage basis. It insures the provision of a sufficient oil supply before starting on a given run, and regulates the amount periodically supplied to the engine cylinder.

The reservoir 1, of the oil delivery unit may be of any preferred form, and is herein shown as of rectangular configuration.

Bearings for reciprocatory pump and valve elements, and for an eccentric operating shaft for the same, are provided, the central axes of which are disposed in planes at right angles to each other, intersecting at the center of figure of the reservoir. The eccentric, pump and valve operating shaft 2, is disposed horizontally and centrally of the reservoir, in aligned tubular bearings 3, 4, the bearing 3 being formed integrally therewith, projecting within and without the reservoir walls, and being of a diameter greater than the shaft, except adjacent its inner end, at which it supports the shaft for rotation.

The bearing 4 has the form of a closure cap providing a tubular extension 5, projecting into the reservoir, within which extension one end of the shaft is free to rotate. The bearing 4 has screw-threaded engagement with the reservoir wall, and is provided with a suitable wrench projection.

The eccentric, indicated at 6, is formed as an integral part of the shaft 2, and is positioned midway between the side walls of the reservoir. The shaft 2 beyond the bearing 3 has a squared extension 7 and beyond this squared extension a short threaded extension 8. The outer projecting portion of the bearing 3 is threaded for engagement by a bearing cap 9 providing a

circular recess 10 at its outer side designed to house the rollers of a ratchet device for rotating shaft 2, which device is hereinafter described in detail.

5 The outer end of the shaft 2, is supported in the bearing opening 11 of the cap 9. Packing 12 surrounds the shaft within the bearing 3, and gland 13 is forced thereagainst by a spring 14 surrounding said 10 shaft and compressed between said gland and cap.

The eccentric 6 is designed to traverse a rectangular yoke or frame element 15, and to engage the interior horizontal parallel 15 faces thereof, for raising and lowering the same. The yoke is provided with upper and lower centrally disposed aligned cylindrical guide extensions 16, 17, the central axes of which intersect the axis of the eccentric shaft 2 at the center of figure of the reservoir. The upper extension 16 is integral with the yoke and is slidably supported at its upper end in a spider 18, placed across a recess of a screw plug 19, in threaded 20 engagement with the opening of the upper wall of the reservoir, which opening is of sufficient size to allow for the introduction or removal of the yoke or for making adjustment or repairs of the mechanism within 25 the reservoir. A liquid filling opening in the plug 19 is closed by a suitable screw cap 20.

The lower end of the extension or valve stem 17 is provided with a conical valve 35 25, which is designed to cooperate with a valve seat at the upper end of a hollow or tubular plunger 40, to control the flow of oil thereto, said valve 25 further cooperating to cap or close and reciprocate the plunger 40 for forcibly delivering definite charges of oil. The structure of the combined oil charge-measuring and charge-pumping mechanism is as follows:

Within a threaded opening in the bottom 45 of the reservoir, axially aligned with and of the same diameter as the upper opening, is screwed a plug 30 having a lower exterior tubular extension 31 and an upper interior tubular or cylindrical extension 32. 50 The upper extension provides a cylindrical bore 33, the wall of said extension having a plurality of diametrically disposed openings 34 therethrough. Against the outer periphery of the extension covering said opening is placed a strainer gauze 35 designed to prevent the entrance of foreign material therethrough.

Within the bore 33 is slidably disposed a block or plunger head 36 having a central passage 37 therethrough, counterbored at 38. The plunger head is further provided with radial passages 37^a communicating with the passage 37 at the bottom of the counter-bore 38 and adjacent the valve 25. The lower end of the passage 37 is threaded

for engagement with the upper end of the tubular plunger 40 extending downwardly and within the bore 41 of the lower extension 31. The upper periphery of the tubular plunger 40 provides a valve seat engageable by the valve 25 slideable within the counter-bore 38, the stem 17 of the valve traversing a threaded plug 38^a engaged in the top of said bore, the upper end of the stem having threaded engagement with the yoke. The valve 25 has only a limited movement between its seat and the lower end of the plug 38^a, so that when the eccentric has moved from its initial position through a relatively small arc of rotation, the valve is unseated and, in its continued upward movement, engages the lower end of the plug 38^a to raise the plunger head 38 and tubular plunger 40, while the eccentric travels through 180° or one-half of its cycle of rotation. During the upward stroke or movement of the hollow plunger, a charge of oil is admitted at its top, either to replace that amount of oil previously forced from the lower portion of the pump cylinder or to fill said cylinder, as in the initial operation of the device. The oil flows from the reservoir through openings 34 and passage 37^a, in said hollow plunger. This up-stroke of the plunger may be said to correspond to a "suction-stroke," although, as a matter of fact, gravity alone acts to replace the oil previously expelled by the down-stroke of the plunger.

The hollow plunger 40 operates within a pump cylinder conduit 40^a formed by a tubular bushing 43, having threaded engagement at its lower end with the bore 41 of the extension 31. Packing 41^a surrounds the plunger 40 above the bushing 43 to prevent the back flow of oil into the bore 33. The bushing 43, adjacent its lower end, has radial passages 44 communicating with an interior annular groove 45 in the bore 41. The groove 45 communicates, through an opening 46, with the interior of a socket 47 formed upon the extension 31, into which socket is screwed the end of a valve-carrying connection 48. This connection 48 is pro-

105 vided with a central bore 49 communicating with the socket 47 and opening 46, and at right angles to the axis of said bore is disposed a spring pressed check valve 50 slideable in a removable bushing 50^a, and normally seated to close a passage 51, communicating with bore 49 and with passage 52,

110 which passage 52 in turn connects with the passage 53 of a pipe 54 attached by union 55 to the end of the connection 48, said pipe 54 being attached to and in communication with the interior of the steam pipe 56. The hollow plunger 40, cylinder 40^a, passages 44, groove 45, opening 46, socket 47, and pas-

115 sage 49 and 51, together form what may be 120 considered a continuous discharge chamber

125 130

or conduit between the valve 25 and the check valve 50, which chamber is filled with oil when the valve 25 is open and while the plunger 40 rises. During the first part of 5 the last half of the cycle of rotation of the eccentric 6, that is, on its down-stroke, the valve 25 is seated to prevent further flow of oil into the upper end of the hollow plunger 40, the oil level therein having been lowered 10 to a predetermined extent by a previous discharge of oil, said valve thereafter acting as a piston to force a determined quantity of oil from the continuous chamber, below said valve, formed as above mentioned, into the 15 passages 52, 53, against the action of the valve 50 and steam pressure in passages 52, 53, and steam pipe 56.

The valve 25 acts both as valve and piston, the hollow plunger 40, forming a means of 20 communication between the reservoir and chamber 40^a, and providing a liquid-tight fit therebetween. The packing 41^a surrounding the plunger in the bore 41, is compressed between the end wall thereof and the end of 25 the bushing 43, to additionally pack the plunger against leakage. As shown in Fig. 1, the valve and plunger are at their limit of downward movement. The lower conical surface of the valve acting as a piston 30 head to discharge the oil from the chamber. The length of plunger stroke determines the amount of charge admitted and expelled, and this length may be varied by correspondingly changing the degree of eccentricity of the eccentric 6. The hollow formation of the plunger 40 practically eliminates the effect of back pressure, which 35 would tend to move the plunger upwardly, practically all of such pressure or thrust 40 being received by the valve 25, which is positively held against upward movement by the yoke and eccentric.

The eccentric shaft 2 is intermittently rotated by ratchet mechanism, a preferred 45 form of which is herein shown as of roller friction type, a dependable means for converting reciprocatory into rotary motion. It is obvious, however, that various types of mechanism may be employed for rotating 50 the shaft 2. The ratchet mechanism herein disclosed, comprises a pair of ratchet wheels 60, 61, mounted non-rotatively upon the squared extension 7 of the eccentric shaft 2. The ratchet wheel 61 is housed within the 55 recess 10 of the cap 9, while the ratchet wheel 60 is housed within the recessed hub 63 of the actuator arm 64, said hub being held upon the shaft by a nut 65 engaged with the threads of the extension 8. Rollers 60 66 are disposed between the teeth of the ratchet wheel 61 and the inner annular surface of the recess 10 for frictionally binding the ratchet wheel and bearing cap 9 together for locking the shaft against reverse 70 rotative or anti-clockwise movement, the shaft 68

in this instance being frictionally clamped to the valve body through the cap 9. A series of rollers 70 are disposed between the ratchet 70 wheel 60 and the inner circular bearing surface of the hub 63, for frictionally clamping and rotatively connecting the hub and ratchet wheel, for rotating the shaft 2 when the arm 64 is oscillated in a forward direction, which causes the rollers to engage between the hub bearing surface and the ratchet 75 wheel, binding the two parts together and releasing the same in a reverse movement of the arm. The hub 63 forms a closure for the recess 10, housing and confining the rollers for the ratchet wheel 61, and cap plate 80 60^a fixed to the hub 63 by screws 64^a, provides a closure for the rollers 70 cooperating with the ratchet wheel 60, and confines the said rollers within the hub. The ratchet actuator-arm 64 connects with one end of a 85 link 72. The opposite end of the link 72 is pivoted to a lever 73 hingedly supported, in this instance, beneath the locomotive running-board. The lever 73 is pivoted with one end of a link 74, the opposite end of the 90 link rigidly connecting with one arm of a lever 75 pivoted as at 76 to a bracket 77. The opposite arm of the lever 75 is pivoted to a link 78, and the opposite end of this link is pivoted to an arm 79 rigidly attached 95 to the main crank pin 80 of the locomotive drive wheel.

The connections between the eccentric shaft-actuator arm 64 and the locomotive crank pin 80 comprises a means for actuating 100 the valve 25 and plunger 40 for a timed delivery of a charge of lubricant to the engine cylinder or shaft, after a predetermined number of drive wheel revolutions. This provides a definite timing means for the distribution and the feeding of the lubricant. The approximate calculation as to the quantity of lubricant required for a known mileage run can be made, which is of material 105 advantage in railroad service where requisitions for oil are issued on mileage basis.

The lever 72 is provided with a series of apertures 73^a for adjustably connecting the lever 64 with said lever, to change throw or stroke of the arm lever for the adjustment 110 of the speed of rotation of the eccentric shaft 2.

It is obvious that the arm 64 may be connected to other moving parts of the locomotive or engine, although its connection with one of the drive wheels is preferable and more convenient, since a more definite basis for computing the approximate consumption of lubricant per mile is furnished.

Having described my invention, I claim:

1. In a force-feed lubricator, a reservoir, a delivery conduit attached thereto, a reciprocable hollow plunger connecting said reservoir and conduit, a reciprocating valve seating at one end of said plunger for con-

trolling the lubricant supply thereto, in one stroke of said plunger, and for providing a closure and plunger head in a reverse stroke for forcing a charge of lubricant through said conduit.

2. In a pressure lubricating device, a reservoir, a liquid discharge conduit attached thereto, a hollow plunger slidable in said conduit for establishing communication between said conduit and reservoir, a valve cooperable with the end of said plunger for respectively opening and raising, and closing and depressing the plunger, for charging said conduit and forcing a charge therefrom.

3. In a pressure liquid-delivery apparatus, a reservoir providing a plunger and delivery conduit, a tubular plunger reciprocable in said conduit for establishing communication between said reservoir and conduit, a valve connected with said plunger, reciprocable with respect thereto, and seating thereagainst, for respectively opening and raising, and closing and depressing the plunger, filling said conduit and forcing liquid therefrom.

4. In a force-feed lubricator, a reservoir valve, a discharge conduit attached thereto, providing an outwardly-opening check valve therein, a hollow plunger reciprocable in said conduit, for connecting said reservoir and conduit, a valve attached to said plunger, reciprocable with respect thereto, for closing and depressing said plunger, and for opening and raising the same, and intermittently rotatable means cooperating with said valve for a timed reciprocation of the same.

5. In a force-feed lubricator, a reservoir having a discharge conduit removably attached thereto, a hollow plunger reciprocable in said conduit and providing a cylindrical head having ports therein, said plunger and ports providing communication between said reservoir and conduit, a valve attached to said cylindrical head, and reciprocable with respect thereto, for respectively closing and depressing said plunger, and opening and raising the same, and means intermit-

tently rotatable, cooperating with said valve for reciprocating the same.

6. In a force feed lubricator, a reservoir having a valve controlled conduit attached thereto, a hollow plunger providing a head having ports therein, said plunger reciprocable in said conduit, and said plunger and ports providing communication between said reservoir and conduit, a valve reciprocably attached to and within said head, adjacent said ports, and cooperable with said conduit, for respectively opening said plunger and raising said head and plunger, and closing said plunger and depressing said head and plunger.

7. In a force feed lubricator, a casing providing a reservoir, plunger cylinder and oil delivery chamber, a reciprocable open ended tubular plunger connecting said reservoir and oil delivery chamber, a valve loosely connecting with said plunger to provide a closure and head for the inlet end thereof, said valve in one stroke of said plunger connecting the plunger inlet end, for admitting oil to said delivery chamber, and seating the same in a reverse stroke for forcing the oil from said delivery chamber, and means for reciprocating said valve and plunger.

8. In a force feed lubricator, an oil supply reservoir, an oil delivery conduit, a reciprocable open ended tubular plunger connecting said reservoir and delivery conduit, a valve providing a closure and head for the inlet end of said plunger, operable with said plunger in one stroke for opening said plunger to the reservoir for admitting oil into and through the plunger and in a reverse stroke closing said plunger and forcibly discharging oil through said delivery conduit, and means for reciprocating said plunger and valves.

In witness whereof, I hereunto subscribe my name, as attested by the two subscribing witnesses.

JOHN WALTER GRANTLAND.
